UNITED STATES PATENT OFFICE.

HARRY MARTIN, OF NEW YORK, N. Y.

SHOEHORN.

Application filed March 10, 1925. Serial No. 14,489.

To all whom it may concern:

Be it known that I, HARRY MARTIN, a citizen of Rumania, and a resident of the city of New York, borough of Manhattan, 5 in the county and State of New York, have invented a new and Improved Shoehorn, of which the following is a full, clear, and exact description.

This invention relates to shoe horns, an 10 object of the invention being to provide a shoe horn which is capable of folding or collapsing, which can be suspended from a button, supported on a key ring or carried in the pocket and occupy but a very small 15 space when not in use.

A further object is to provide a shoe horn composed in part of rigid material and in part of flexible material, so coupled that they function together as a shoe horn and yet permit the device to be folded into 20 comparatively small space.

With these and other objects in view, the 25 invention consists in certain novel features of construction and combinations and arrangements of parts which will be more fully hereinafter described and pointed out in the claims.

In the accompanying drawings—

Figure 1 is a perspective view taken from 30 the rear of the shoe horn;

Figure 2 is a view in elevation taken from the front of the shoe horn;

Figure 3 is a view showing the shoe horn folded;

Figure 4 is a view in longitudinal section 35 on the line 4—4 of Figure 3.

My improved shoe horn comprises a rigid member, 1 and a flexible member 2. The rigid member 1 may be of metal or any other suitable material, of general concavo-convex shape in cross section, and curved 40 at its free end so as to present a rigid guide for the heel when forcing the foot into a shoe, as is customary in the art. This rigid member is approximately half the length of 45 the ordinary shoe horn and at its inner end is provided with a transverse slot 3 to receive a strap 4 on the flexible member 2.

The flexible member 2 may be of leather, 50 fabric or any other flexible material which is suitable for the purpose and which comprises a sheet of the desired shape and size having at its ends integral strap members 6 and 7, one of said strap members 6 being projected through the slot 3 and secured to the other strap member 7 by means 55

of eyelets or other securing devices 8 so as to form a complete strap integral with the member 2.

This member 2 at its outer end is formed 60 with a buttonhole 9 to receive a button on the trousers or other part of the wearing apparel so as to conveniently support the device in suspended form, and an eyelet 10 is provided in the flexible member to receive 65 a key ring or other suitable support.

On the strap 4 a hook 11 is secured and under this hook the free edge of the rigid member 1 may be positioned so as to hold the device in folded form as indicated in 70 Figures 3 and 4. The rigid member may be positioned under the hook 11 and released therefrom by a lateral movement, and when in position under the hook the device will occupy but approximately half its 75 normal size so that it may be conveniently carried in the pocket or from the key ring of the user and occupy but a very small space.

When in use, the operator places his 80 finger under the strap 4 and grasps the flexible portion 2, inserting the rigid portion 1 into the heel of the shoe and thus providing a convenient means for gripping the device while in operation. When not 85 in use, the rigid member is positioned under the hook 11 as above explained.

While I have illustrated what I believe to be a preferred embodiment of my invention it is obvious that various slight 90 changes and alterations might be made without departing from my invention, and hence I do not limit myself to the precise details set forth but consider myself at liberty to make such slight changes and 95 alterations as fairly fall within the spirit and scope of the appended claims.

I claim:

1. A shoe horn, comprising a rigid member and a flexible member, the rigid member having a slot therein, and a strap on the flexible member positioned through said slot.

2. A shoe horn, comprising a rigid member and a flexible member, the rigid member having a slot therein, and a strap on the flexible member positioned through said slot, said flexible member having a buttonhole and an eyelet therein.

3. A shoe horn, comprising a rigid member and a flexible member, the rigid member having a slot therein, a strap on the

flexible member positioned through said slot, and a hook on the strap adapted to receive the free end of the rigid member and hold the flexible member and rigid member side by side.

4. A shoe horn, comprising a rigid member having a slot therein, a flexible member having strap tabs at both ends, one of said tabs projected through the slot of the

rigid member, means for securing the tabs together, and a hook on the tab adapted to receive the free end of the rigid member.

5. A shoe horn, comprising a rigid foot receiving member, and a flexible handle member connected thereto, said members adapted to fold one upon the other.

HARRY MARTIN.
